KNIFE HANDLE

Harry M. Gustafson, Chicago, Ill., assignor to Simmons Slicing Knife Company, Chicago, Ill.,
a corporation of Illinois

Application October 8, 1948, Serial No. 149,027

Term of patent 14 years

(Cl. D22—3)

To all whom it may concern:

Be it known that I, Harry M. Gustafson, a citizen of the United States, residing in Chicago, Cook County, State of Illinois, have invented a new, original, and ornamental Design for a Knife Handle, of which the following is a specification, reference being had to the accompanying drawing, forming a part thereof.

Fig. 1 is a perspective view of a knife handle, showing my design;

Fig. 2 is a side view of the knife handle;

Fig. 3 is a top plan view of same; and

Fig. 4 is an end view of the knife handle taken from the right of Fig. 2.

I claim:

The ornamental design for a knife handle, as shown.

HARRY M. GUSTAFSON.
